MIXING DEVICE

Orlando H. Lind, Auburn, Calif.

Application August 11, 1950, Serial No. 178,831

6 Claims. (Cl. 259—143)

1

The invention relates to mixing devices for stirring or distributing solid particles in a liquid vehicle, such as pigment in paint, and also relates to a new and useful method for effecting such mixing action.

The present application is a continuation-in-part of my co-pending application Serial No. 68,015, filed December 29, 1948, now abandoned.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

An object of the invention is to provide a simple and efficient device which can be introduced and operated within commercial containers of paint and similar solid-liquid mixtures so as rapidly and thoroughly to intermix the sedimented particles with the liquid vehicle.

In the mixing of paint, liquid fertilizer and the like, it has been common to use a paddle or stick, in an endeavor to scrape from the bottom of the can the heavier materials and to cause the heavier ingredients to become thoroughly mixed with the lighter liquids. This is particularly true in the mixing of paints. With an ordinary wooden paddle or stick it is almost impossible to thoroughly lift the heavier particles of lead or other solid pigment ingredients from the bottom and mix them with the oils and, as a result, the top portion of the liquid is always more fluid than the bottom portion.

The invention provides a device which may be inserted into a paint can, bucket or other container and, by vertical oscillation or up-and-down movement effect a rapid and thorough intermixure of the solid and liquid particles. By producing a unique flow and counter-flow of currents within the lower part of a container of paint, the solid particles are caused to be lifted from the bottom of the container and intermix rapidly and very intimately with the oil or other liquid vehicle. A scouring effect is also created so that sedimentation or sticking of solid particles to the surface of the container is overcome. The

2

invention also involves a novel method of creating the currents and flowage of fluid and solid particles for the purposes specified.

Other objects of the invention are to provide a mixing device for paint or the like which may be readily cleaned, may be suspended in the container between uses and may be used without danger of spotting or contaminating the user or the surrounding articles. The device is also of such simple construction that it is inexpensive to manufacture.

Of the drawings:

Fig. 1 is a side elevation of a device embodying the invention shown in use in a container of paint or the like, the container being shown in section;

Fig. 2 is an enlarged fragmentary vertical section of the plates forming the principal operative elements of the invention, with parts broken away;

Fig. 3 is an enlarged fragmentary view of a container with the lower portion of the agitating device, shown in section therein, on the down-stroke;

Fig. 4 is a view similar to Fig. 3, with the device on the up-stroke;

Fig. 5 is a transverse vertical section of a plate and cup forming a modified form of the invention;

Fig. 6 is a top plan view of the device shown in Fig. 5 with a portion of the upper plate broken away; and

Fig. 7 is a view similar to Fig. 5 of a second modification.

Essentially the invention comprises a cup-like member mounted at the end of a handle adapted to be moved up-and-down in a container of paint or the like. The base plate of said cup member is perforated so as to permit fluid and small particles of solid matter to pass therethrough. A second plate is slidably mounted on the handle to lie above and normally in contact with the base plate of the cup member. The upper plate is also perforated and preferably the perforations thereof or the major portion of same are out of register with those in the lower plate. As the two plates are plunged downwardly through the fluid, sedimented particles at the bottom of the container are forced in jet-like streams through the openings in the lower and upper plates. Upon the up-stroke, however, the upper plate moves into contact with the lower, cutting off the openings therein and thereby providing a sealed lift for raising the materials which have been flushed from the bottom by the down-

stroke. Thus, in addition to causing substantial cross-currents agitating the solid particles, the device provides an effective jet-like upward propulsion of said particles on the down-stroke, a bodily lifting thereof on the up-stroke and also the up-stroke provides a turbulence in the wake of the rising plates which effectively scours and further agitates the contents of the container.

It will be understood that the foregoing general description and the following detailed description as well are exemplary and explanatory but are not restrictive of the invention.

Referring now in detail to the present preferred embodiment of the invention, illustrated by way of example in the accompanying drawings, a cylindrical container 5 of paint or the like is shown with a body of liquid comprising partially mixed oils and heavier solid pigment particles which tend to settle to the bottom in a well-known manner. The agitating device of the invention comprises a cup-like member consisting of a preferably flat bottom plate 7 with an upturned cylindrical rim 8, which is preferably, but not necessarily, imperforate. Centrally disposed of the plate is an upstanding stem 9 to which a handle is attached as hereinafter described. While the cup is shown as cylindrical, it is not necessarily circular in cross-section but may be of other shapes.

In accordance with the invention, the bottom plate 7 is provided with a plurality of openings 11 which may be distributed in a circle adjacent the rim 8 as shown, but which are preferably distributed over the surface of the bottom plate more uniformly, as in concentric circles as shown in Fig. 6, for example. While a circular arrangement of the openings 11 is a convenient one, said openings may be arranged in any suitable manner so as to cooperate with the openings in the upper plate hereinafter described. The openings themselves, while shown as circular, may be of any desired cross-section. They should be sufficiently large to permit free passage of paint fluid and solid particles therethrough and in practice, with one size of the device, an opening of about $\frac{1}{8}$ " is provided in a cup having the diameter of about $5\frac{1}{4}$ ". It will be understood that these dimensions are by no means critical and may be varied considerably as desired. In practice, several sizes are provided to accommodate containers of various ranges of sizes. Furthermore, there is no critical relationship between the diameter of the device and the diameter of the paint container, as the device may be used in paint cans barely large enough to receive it, or alternatively in very much larger containers.

In accordance with the invention a second plate 13 is provided to lie above and parallel to plate 7. The upper plate 13 is adapted to slide freely axially with respect to plate 7 and for that purpose is loosely collared about the central stem 9. As shown, an upstanding collar 12 is provided to guide the plate 13 on its vertical movements with respect to the stem, but in practice such a sleeve or collar is not essential as the plate 13 may be simply provided with a suitably large loose fitting central opening or hub around the stem 9. When held vertically and at rest, the upper plate 13 lies on plate 7.

A plurality of openings 14 are provided in plate 13 for the flow of fluid and particles. Said openings may be of the same size as the openings 11 in the lower plate (Figs. 3 and 4) or they may be of different sizes (Figs. 5-7). However, the openings 14 are preferably arranged out of regis-

ter with the openings 11 so that when the two plates are together, as shown in Figs. 4, the two plates present a surface substantially closed to the passage of fluid. Conveniently the openings 5 in the upper plate may be arranged in concentric circles staggered or out of register with respect to the openings 11 in the lower plate, and such arrangements are shown in Figs. 3-7. However, any other distribution of the openings may be made so that they do not normally register with the openings 11 in the lower plate. The diameter of upper plate 13 is such that it fits loosely within the rim 8 of the lower cup so as to have completely free up-and-down motion with respect thereto. While the plate 13, shown in Figs. 1 to 4, is slightly less in diameter than the interior of the cup, it may be substantially less as shown in the modifications of Figs. 5-7.

The relation between the stem 9 and the plate 20 1 is essentially that of a vertical rigid handle which extends upwardly to any desired extent so that the handle may be grasped outside the paint container and for such purpose the stem 9 may itself be extended as far as desired. For convenience in cleaning and other purposes, however, I have shown a detachable handle 18 comprising a tube in which a plug 17 is set at the lower end. The plug 17 and the upper end of the stem 9 are preferably stepped and the assembly joined by a transverse cotter pin 19 or the like. Thus the handle may be removed for cleaning, storing, etc. For convenience in use, a hook 21 may be formed on the handle 18 so that same may be hung over the edge of the container as shown in Fig. 1.

Referring now to the modification shown in Figs. 5 and 6, I have found that it is desirable to prevent the upper plate from lying in flat contact with the lower plate because of their 40 tendency to adhere through suction or surface tension. To prevent this undesirable adherence, the upper plate 130 may be formed with a plurality of corrugations, preferably circular, so that it will come in contact with the upper surface of plate 7 only on a plurality of spaced rings 131. As shown, the openings 132 and 133 in said upper plate are cut through the elevated portions of the corrugated plate and disposed, as shown, so as to be out of register with the openings 11 in the lower plate.

In the modification shown in Fig. 7, the same effect of spacing the two plates from overall surface contact is effected by forming elevated lips 140 around the openings 11 in said lower plate. 50 In this case the upper plate 13 may be flat and the openings 14 and 141 therein staggered or out of register with the openings 11 in the lower plate, as shown.

In the operation of the device embodying my 60 invention, a novel method of mixing is involved. When the mixing device is forced downwardly, as shown in Fig. 3, the inertia of the opposing fluid and the upper plate 13 keeps plate 13 spaced above the lower plate 7. This spacing frees the 65 openings 11 and 14 so that jets of fluid and pigment are forced upwardly through said openings. This imposes an upward and transverse movement upon the fluid as it rises through the openings 11 and crosses over to escape upwardly through the openings 13. Thus a forceful series of movements and cross-currents are imposed upon the settled pigment and it is elevated and forced into the lighter oils above by the downward movement of the device. It will also be clear that when the 70 edges of the device are near the inner walls of a

container (Fig. 3), a similar upward flow of materials is imposed between the rim 8 of the cup and the walls of the container. Fluid also travels upwardly between the inner surface of the cup-rim 8 and the inner edge of the plate 13.

When the motion of the device is reversed, as on the up-stroke (Fig. 4), plate 13 is forced downwardly and into contact with plate 7, thus blinding the openings 11-14. The raising of the cup imparts a positive lifting to the solid materials which have previously been forced above the bottom of the cup by the down-stroke action described. The lifting action, therefore carries substantial quantities of the solid materials upwardly into the upper levels of the fluid. At the same time the rising movement of the cup which now has an effectively closed bottom, also exerts a suction action below it, drawing fluid and solid particles into its wake where a substantial and effective turbulence is created. Thus on both the up-stroke and on the down-stroke, a very positive and effective mixing action is imparted to the materials in the container.

The invention in its broader aspects is not limited to the specific mechanisms shown and described but departures may be made therefrom within the scope of the accompanying claims without departing from the principles of the invention and without sacrificing its chief advantages.

What I claim is:

1. A mixing device including in combination a plunger having a stem movable up and down in a fluid container, a cup with a perforate bottom fixed to the lower end of the stem, a detachable perforate plate lying on the bottom of the cup and slideable on the stem toward and away from said bottom, means on said plate and said stem for limiting the movement of said plate away from said cup bottom, the perforations in the cup bottom and in the plate being out of register so that the openings in the bottom of the cup are substantially closed when the plate is in contact with said bottom, and the plate being moved away above the cup bottom when the plunger is forced down in the fluid and being held in contact with the bottom when the plunger is lifted through the fluid.

2. A mixing device including in combination a plunger having a stem movable up and down in a fluid container, a cup with a perforate bottom and a solid upstanding rim fixed to the lower end of the stem, a detachable perforate plate lying on the bottom of the cup and slideable on the stem toward and away from said bottom, means on said plate and said stem for limiting the movement of said plate away from said cup bottom, the perforations in the cup bottom and in the plate being out of register so that the openings in the bottom of the cup are substantially closed when the plate is in contact with said bottom, and the plate being moved away above the cup bottom when the plunger is forced down in the fluid and being held in contact with the bottom when the plunger is lifted through the fluid.

3. A mixing device including in combination a plunger having a stem movable up and down in a fluid container, a cup with a perforate bot-

tom fixed to the lower end of the stem, a detachable perforate plate lying on the bottom of the cup and having a centrally disposed tubular guide member projecting upwardly so that the plate member is slideable on the stem, toward and away from said bottom, means on said stem for engaging said guide member for limiting the movement of said plate away from said cup bottom, the perforations in the cup bottom and in the plate being out of register so that the openings in the bottom of the cup are substantially closed when the plate is in contact with said bottom, and the plate being moved away above the cup bottom when the plunger is forced down in the fluid and being held in contact with the bottom when the plunger is lifted through the fluid.

4. A device as defined in claim 3 in which there is a detachable handle having a tubular end detachably fitted on the upper end of the stem whereby the movement of the plate away from the cup bottom is limited by the engagement of the tubular guide member with the base surface of the handle.

5. A mixing device including in combination a cup with a perforate bottom, a perforate plate lying on the bottom of the cup and movable upwardly away from said bottom, the perforations in the cup bottom and in the plate being out of register so that the openings in the bottom of the cup are substantially closed when the plate is in contact with said bottom and open when the plate is above said bottom, and means for moving the cup and the plate up and down in a container of a fluid mixture and spacing means for preventing continuous coplanar contact of the cup bottom and plate.

6. A mixing device including in combination a plunger having a stem movable up and down in a fluid container, a cup with a perforate bottom fixed to the lower end of the stem, a detachable perforate plate lying on the bottom of the cup and having a centrally disposed tubular guide member projecting upwardly so that the plate member is slideable on the stem, toward and away from said bottom, means on said stem for engaging said guide member for limiting the movement of said plate away from said cup bottom, the perforations in the cup bottom and in the plate being out of register so that the openings in the bottom of the cup are substantially closed when the plate is in contact with said bottom, and the plate being moved away above the cup bottom when the plunger is forced down in the fluid and being held in contact with the bottom when the plunger is lifted through the fluid and spacing means for preventing continuous coplanar contact of the cup bottom and the plate.
